UNITED STATES PATENT OFFICE.

ALBERT T. MAGAGNOS, OF CORONA, NEW YORK, ASSIGNOR TO GENERAL BOARD OF THE YOUNG MEN'S CHRISTIAN ASSOCIATIONS, OF NEW YORK, N. Y., A CORPORATION OF NEW YORK.

DESIGN FOR AN ASSOCIATION SWIMMING BADGE.

Application filed February 12, 1926. Serial No. 18,505. Term of patent 7 years.

To all whom it may concern:

Be it known that I, ALBERT T. MAGAGNOS, a citizen of the United States, residing in Corona, Long Island, in the county of Queens and State of New York, have invented a certain new, original, and ornamental Design for Association Swimming Badges, of which the following is a specification, reference being had to the accompanying drawings, forming a part thereof, and of which—

Figure 1 is a front elevation, and Fig. 2 is an edge view of an association swimming badge showing my new design.

I claim:

The ornamental design for an association swimming badge as shown.

A. T. MAGAGNOS.
